UNITED STATES PATENT OFFICE.

DE WANE B. SMITH, OF UTICA, NEW YORK.

DESIGN FOR AN AUTOMOBILE-BODY.

57,936.

Specification for Design.

Patented May 17, 1921.

Application filed November 20, 1920. Serial No. 425,570. Term of patent 7 years.

To all whom it may concern:

Be it known that I, DE WANE B. SMITH, a citizen of the United States, residing at Utica, in the county of Oneida and State of New York, have invented a new, original, and ornamental Design for an Automobile-Body, of which the following is a specification, reference being had to the accompanying drawing, forming part thereof.

The figure is a plan view of an automobile body showing my new design.

I claim:

The ornamental design for an automobile body as shown.

DE WANE B. SMITH.
